E. D. GREEDY

PORTRABLE BOOKRACK

Filed April 10, 1923

UNITED STATES PATENT OFFICE.

EDWARD D. GREEDY, OF CEDAR RAPIDS, IOWA, ASSIGNOR TO LE FEBURE LEDGER COMPANY, OF CEDAR RAPIDS, IOWA, A CORPORATION OF IOWA.

PORTABLE BOOKRACK.

Application filed April 10, 1923. Serial No. 631,227.

To all whom it may concern:

Be it known that I, EDWARD D. GREEDY, a citizen of the United States, residing at Cedar Rapids, in the county of Linn and 5 State of Iowa, have invented new and useful Improvements in Portable Bookracks, of which the following is a specification.

This invention is designed to facilitate the handling of books or ledger binders and 10 particularly books and loose leaf ledgers used in connection with book-keeping or posting machines. With this structure a frame is provided preferably carried on rollers so that the whole may be readily 15 rolled into convenient position for use and into and out of a vault. In order to make it available for such movement and still give it capacity it is desirable to have a series 20 of shelves for carrying the books with such a mounting as to be moved with book contents into and out of the frame. It is further desirable to have these move into and 25 out of both sides of the frame and the present invention contemplates such a structure.

Details and features of the invention will appear more fully from the specification and claims.

The invention is illustrated in the accompanying drawings as follows:

Figure 1 is a side elevation of the device, partly in section, on the line 1—1 in Fig. 2.

Fig. 2 an end elevation, partly in section, on the line 2—2 in Fig. 1.

Fig. 3 a section on the line 3—3 in Fig. 2.

Fig. 4 a plan view of one of the book holders.

Fig. 5 a section on the line 5—5 in Fig. 2.

1 mark the posts of the frame. A top plate with flanged edges 2 is arranged over 40 the four posts of the frame and secured preferably by bolts 3. Side portions 4 extend across the sides of the frame and these are in the form of angle irons and are secured by rivets 5. Cross bars 6 extend 45 across the ends of the frame, being secured to the posts by rivets 7. Three rollers 8, 9 and 10 extend through a channel iron 11, the iron being provided with a bearing plate 11a.

Shelves 12 are formed of sheet metal and 50 extend between the end angle bars 13. The angle bars 13 not only extend the width of the shelves but also to the rear of the shelves and between the rollers 8, 9 and 10, the shelves at the angle bars from one side being between the rollers 8 and 9 and those at

the opposite side between the rollers 9 and 10 so that when the shelves are moved into the frame these parts overlap the shelves. The angle bars have the ends turned down at 14 engaging the rollers 9 and 10 so as to 60 form a stop for the outward position of the shelves. The shelves operate over guide rollers 15 extending between the posts and guide lugs 15a so that when the shelves are pulled out to the position shown at the left 65 of Fig. 2 the fronts of the shelves are held between the rollers 15 and lugs 15a while the extensions of the angle bars 13 are held by the rollers 8 and 9 and 9 and 10. Thus the shelf has a perfect support both in and out 70 of the structure so as to readily support books mounted on the shelves and permit of the movement of the shelves with the books in place. The shelves have the downward lip 16 at their outer edges which form 75 stops against the rollers 15 so as to locate the shelves when moved into the frame.

Book holders having bases 17 are mounted on the shelves. These bases are preferably 80 of sheet metal having out-turned edges 18 with outwardly extending flanges 19. Plates 20 are arranged along the sides of the edges 18 and these have slots 21 through which screws 22 extend. U-shaped bars 23 are secured by rivets 24 on the edges 18 and on 85 the plates 20 and extend upwardly at a slight inclination so as to readily hold an inserted book 22a. Slots in the plates 20 permit the moving of one of the bars 23 to accommodate 90 different sizes of books. The holders are preferably pivotally mounted on the shelves and on the top of the frame at the position 95 shown, the bases having openings 25 through which pivot pins 26 extend. This permits the swinging of the book so that the books may be more readily observed in use. It will be understood that the book rack as a whole may be moved adjacent to the book-keeping machine, or the like. A shelf 27 is pivotally mounted on a rod 28 extending 100 between the end posts. This shelf is supported in a horizontal position by a brace 29. The brace 29 is carried by a hook 30 at the lower end of a bar 31. The bar 31 is secured to the channel 11 by a rivet 32 and 105 forms a stop holding the rollers 8, 9 and 10 in place. By disengaging the brace 29 the shelf may be dropped down to a vertical position thus reducing the size of the rack as a whole so that it can be readily housed 110

in the ordinary vault. The whole device is mounted on wheels 33 so that it may be readily moved as it is used.

It will be noted that these shelves moving out from both sides will retain the books in position to be observed or to be worked from in posting from both sides of the device and they may be left in these shelves during working hours for reference purposes. It will also be noted that while I have shown the device adapted for use from both sides in the broader aspects of the invention it may be formed with the shelves at one side only.

15. What is claimed as new is:—

1. In a portable book rack, the combination of a frame; rollers arranged centrally of the frame; shelves movably mounted between said rollers; bars at the end of the frame preventing the removal of the rollers; a folding shelf at the end of the frame; a brace for the folding shelf; and a hook on one of the bars on which the brace may rest when the shelf is raised to a horizontal position.

2. In a portable book rack, the combination of a frame, shelves slidingly mounted in the frame and extensible from opposite sides of the frame, one shelf being arranged 30 above the other and the upper shelf leaving a space above the lower shelf uncovered with the upper shelf in its inner position in the frame, a book rack mounted on the lower shelf and movable with it into and 35 out of the frame, a book rack on the upper shelf, said shelves with their racks being adapted to move into and out of the frame independently and simultaneously.

3. In a portable book rack, the combination of a frame, shelves slidingly mounted in the frame and extensible from opposite sides of the frame, one shelf being arranged

above the other shelf and said upper shelf having extensions which maintain it in a horizontal position when the shelf is extended, and provide a space over the lower shelf with the upper shelf in its inner position, and a book rack on the lower shelf movable, when the shelf is moved into the frame into the space between the extensions. 50 45

4. In a portable book rack, the combination of a frame, a series of pairs of shelves arranged in staggered relation vertically and extensible from opposite sides of the frame, the top shelf of each pair of shelves having extensions for holding the shelf in a horizontal position when drawn outwardly from the frame and leaving a space at the rear of said shelf when the shelf is in its inner position and the lower shelf of each pair lying directly under said space when said shelves are not extended whereby both shelves of each pair of shelves may be loaded when they are extended and the shelves telescoped so as to enclose the said loads within said frame. 55 60 65

5. In a portable book rack the combination of a frame, a pair of shelves arranged in staggered relation vertically and extensible from opposite sides of the frame, the top shelf having extensions for holding the shelf in horizontal position when drawn outwardly from the frame and providing a space at the rear of said shelf when the shelf is in its inner position and the lower shelf lying directly under said space when said shelves are not extended whereby both shelves may be loaded when they are extended and the shelves telescoped so as to enclose said shelves within the frame. 70 75 80

In testimony whereof I have hereunto set my hand.

EDWARD D. GREEDY.
